tion of Delaware

Application December 12, 1925, Serial No. 74,938

29 Claims. (Cl. 179—171)

This invention relates to the use of amplifiers, oscillators, detectors, modulators and any other type of device using vacuum tubes in which it is desirable that the input bear a definite relation to the output. Particularly, the invention relates to the control of the ratio of the input to the output so that a true reproduction of the input will result according to the design for which the apparatus was built. The embodiment herein disclosed is an amplifier, and while the explanation following will be limited to the use of amplifiers, requiring a linear characteristic, it is not intended that the principles stated be so limited.

15 The causes of the non-linear characteristic of amplifiers such as can now be built, are:—

1. At a certain amplitude of input and output the vacuum tubes begin to draw grid current and the regulation of the grid excitation circuits together with regulation within the tubes, due to a portion of the emission being taken by the grid, cause a departure from the normal amplitude characteristic.

2. Even if the tubes could be designed to operate over the whole range of their direct current output without grid current their characteristics introduce some departure from a linear characteristic.

The first cause can be relieved to some extent by modifications in the design of the tubes or by running with low output from the tubes. There has been no apparent way for eliminating distortion due to the second cause.

30 A method for eliminating, or very greatly reducing the departure from a non-linear characteristic, due to any cause, is shown schematically in the drawings hereto annexed.

The scheme consists of a method for automatically causing the amplification of one or more stages of an amplifier system to be varied by varying the grid bias to keep a constant ratio between the input and output amplitudes of the amplifier system.

35 This is accomplished by coupling two rectifier circuits respectively to the input and output circuits and applying their rectified currents differentially to a resistance or reactance common to both rectifier circuits. The rectified current through the common resistance or reactance produced by each rectifier is proportional to the alternating current voltage of the coupling in the circuit and normally if their is a correct ratio of output to input the two rectified currents will be equal and produce no voltage drop in the common reactance.

However, if the ratio of output to input does not remain constant at the correct value the two rectified currents will become unequal and there will be a resultant current and voltage drop in the common resistance. This voltage drop is utilized to vary the grid potential, and therefore the amplification, of one or more stages of the amplifier system in such a way as to correct the ratio of output to input.

40 The time constant of the rectifier circuits, of course, is such that the time required for the correction to take place is small compared with the modulating frequency of the currents to be amplified.

45 As an alternative to the method which has been described it is possible to correct the dropping of the amplitude characteristic of an amplifier due to grid rectification only. In this method the rectified direct current of one stage of amplifier is used to change the bias and amplification of another stage in such a manner as to correct the characteristic.

50 In both the methods which have been described it is very desirable to use the push-pull amplifier circuit so that rapid corrections of the bias potential in an amplifier will not set up surges in the amplifier output which could cause oscillations or damage to the system. However, other types of amplifiers, modulators, or oscillators might be used in the same way.

55 Further and more specific advantages will be observed in connection with the annexed detailed description, claims and drawings in which:—

Fig. 1 shows one arrangement for producing these results in a multi-stage amplifier, and

Fig. 2 shows a slightly different method.

1 shows the input terminals to the input transformer 2 coupled to the grids of tubes 4 and 5. The middle point of the transformer secondary is connected to the bias battery 3 which gives a constant bias to the grids. The plates of these tubes are energized by the high potential battery 1 through the connection 8 of the output transformer 7.

40 The oscillations thus produced pass through the transformer 9 to the second stage amplifying tubes 11 and 12. The filaments of these tubes are connected as in the first stage to the negative terminal of the high potential battery and also to another conductor at 14. The grids of these tubes are connected to another bias battery 10. The plates of these tubes are energized through connection 16 and oscillations are introduced into the transformer 15. This transformer is connected to transformer 17 of the 3rd stage, 50

having tubes 18 and 19. The grids of these tubes are biased by the battery 20 as in the case of the first stage. The plates are energized through the connection 21 and the output appears in the coil 22.

To the first input transformer 2 or to the input circuit there is variably coupled a third winding 6 and to the output transformer or output circuit there is also variably coupled a third winding 23. These two windings are connected together so as to be approximately in phase with each other through rectifiers 24 and 25 and the resistances or reactances 26 and 27 variable if desired. Between these is a third resistance or reactance 28 with the by-pass condenser 29 for the radio frequencies. To this same mid-point, a third connection is made at 30 to the other side of the bias battery 10. It can thus be seen that the bias produced by the battery 10 on the grids of the tubes 11 or 12 will be modified by any potential difference across resistance or reactance 28.

The number of turns on coils 6 and 23 are so selected that with the normal amount of amplification there will be no flow of current through 28. If more current is passed through rectifier 24 than through rectifier 25, a potential difference would exist in one direction across 28. If more passes through 25 than 24 a reverse potential difference will exist. Thus, the bias produced by battery 10 will be added to or subtracted from by the amount of the potential difference across 28, and in direct ratio to the amount of power unbalance between the coils 6 and 23.

If the proper couplings are obtained in the input and the output transformers, a constant ratio of power transformation may be obtained in the coils 6 and 23.

In the operation of this arrangement, the output may be slightly decreased for the very small amount of power input but for large or average amounts of power input, a much greater amount of the power output would be obtained due to the automatic grid bias regulation. In this way, any natural characteristic of the amplifier system as a whole resulting from excess load will be obviated to a considerable extent. This will result in a better operation characteristic in the amplifier and make it graphically nearly a straight line.

With reference to Fig. 2, 32 are the input terminals connected to transformer 33. The tubes 36 and 37 of the first stage of amplification have their plates connected through the transformer 39 and are energized by the battery 47. The bias of the first stage is obtained on the grids by the source 35 connected to the negative of the battery 47 and to the filament of the tubes in the second stage 41, 42. The output of the second stage has a suitable transformer 44 energized at the connection 43 by the high potential battery 47. The output is taken off at the terminals 45. In the second stage the grid bias battery 40 is connected to the middle of the secondary transformer 39. The other side of the bias battery 40 is connected to conductor 34 which is directly connected to the filaments of the first stage. Between this conductor and the filaments of the second stage is the resistance, reactance or other impedance 46.

In this arrangement it is obvious that the grid current of tubes 41 and 42, which must be a function of the input power, affects the potential difference between grid and filament of tubes 36 and 37 through its effect upon the potential drop

through element 46. This current will produce a voltage drop across 46 which will, in turn, modify the effective bias given to the grids of the first stage by source 35 and the flow of first stage anode current through element 46. It is possible, with this arrangement, to obtain a straight line operating characteristic throughout the normal range of operation of this arrangement. Proper selection and adjustment of the circuit elements, particularly of impedance 46 will effect this characteristic.

It is not intended to be limited by the construction herein set forth but as indicated before, this arrangement could be used with modulators, oscillators, detectors, etc., and proper equivalents could be substituted for those used at present.

I wish to be limited only by the scope of the following claims:

1. In combination, several electron emission tube stages, grid bias means, input and output circuits, comparison circuits coupled with said circuits and including rectifying and impedance elements, and means coupling the bias means and the impedance elements to vary the grid bias according to the ratio of currents in the input and output circuits.

2. In combination, several electron emission tube stages, grid bias means, circuits coupling the input and output circuits including adjustment means, rectifiers for rectifying input and output energy, and means across which rectified current from the rectifiers tends to create a potential gradient, and means to affect the bias means in a manner dependent on the said potential gradient in order to obtain automatic modification of the bias means.

3. In combination, an amplifier having an adjustable ratio of amplification, input and output circuits, means coupling the input and output circuits to obtain resultant energy which is a function of the ratio of the input to the output of said amplifier, and means for adjusting the ratio of amplification in response to said resultant energy in order to give the amplifier a desired operating characteristic.

4. The method of preventing distortion in oscillation devices which includes the steps of comparing the actual ratio of input to output with a desired ratio, for all values of input, and automatically varying the characteristics of the oscillation devices in response to the difference between the actual and desired ratios to reduce the difference.

5. The method of preventing distortion in oscillation devices by keeping the ratio of input and output constant for all values of input up to the maximum which includes comparing the actual ratio of input to output with a desired ratio at every instant during the oscillation cycle and controlling the characteristic of the oscillation device during the oscillation cycle to lessen the difference and obtain the desired ratio.

6. A distortionless amplifier for producing in its output circuit an exact amplified replica of the wave applied to its input circuit comprising several electron emission tube stages, grid bias means, input and output circuits, means associated with said circuits for detecting distortion, and, means for affecting the bias means in response to said distortion detecting means to obviate the distortion whereby the output of said amplifier is substantially an exact amplified replica of the input.

7. The method of obtaining a desired charac-

- teristic from an amplifier employing an electron emission tube subjected to grid rectification thereby having a characteristic different from that desired which includes combining with input energy to a tube fluctuating energy derived from the output energy of the tube such that the altered resulting input energy causes an energy output from the apparatus which is in a desired substantially straight line relation to the original 10 input energy to the apparatus.
8. The method of obtaining a linear amplification characteristic from an amplifier subject to grid rectification employing an electron emission tube having a non-linear characteristic which 15 includes combining with the input energy to a tube, relative to the input energy, low frequency fluctuating energy derived from the output and input energies of the tube of such magnitude and phase that the resulting altered input energy 20 causes an energy output from the amplifier which is in linear relation to the energy input to the amplifier.
9. The method of obtaining a desired characteristic from an electron emission tube stage employing an electron emission tube having a characteristic different from that desired which includes continuously detecting the magnitude of the departure of the output and the input of the stage from the desired characteristic and simultaneously 25 commensurately altering the wave form of input energy applied to a tube grid in response to the detected departures to obtain on the grid an artificial wave of such form that the resulting output wave is in the desired relation to 30 the original input wave.
10. The method of obtaining a linear amplification characteristic from an amplifier employing an electron emission tube having a non-linear characteristic which includes continuously comparing the input to output ratio with that desired and altering the wave form of input energy in response to departure from the desired ratio to obtain an artificial input wave of such form that the resulting output wave is in 35 linear relation to the original input wave.
11. The method of obtaining a linear amplification characteristic from an amplifier subjected to grid detection, employing a plurality of electron emission tubes arranged in cascade and, having non-linear characteristics when the normal grid bias is constant which includes so varying the normal grid bias of one of said tubes, upon variation of input energy to the amplifier, that the resultant output from the amplifier follows a linear characteristic.
12. The method of obtaining a linear amplification characteristic from an amplifier employing an electron emission tube having a non-linear adjustable characteristic which includes detecting the magnitude of the departure from a linear characteristic during variation of the input to the amplifier and commensurately adjusting the tube characteristic in response to the detected departure to counteract the departure.
13. The method of obtaining a linear amplification characteristic from an amplifier employing an electron emission tube having a non-linear characteristic when the normal potential in one of its associated circuits is constant which includes detecting the magnitude of the departure from a linear characteristic and commensurately varying the normal potential in the associated circuit in response to the detected departure to so change the characteristic that the departure is counteracted.
14. The method of obtaining a linear amplification characteristic from an amplifier employing an electron emission tube having a non-linear characteristic when the normal grid bias is constant which includes detecting the magnitude of the departure from a linear characteristic and commensurately varying the normal grid bias in response to the detected departure to counteract the departure.
15. The method of obtaining a linear amplification characteristic from an amplifier employing an electron emission tube having a non-linear amplification characteristic which includes obtaining energy which is a function of the input energy, obtaining energy which is a function of the output energy, comparing their ratio with a desired ratio, obtaining corrective energy which is a function of the departure of the actual ratio from the desired ratio, and using the corrective energy to vary the grid bias of a tube to make the ratio of input to output of the amplifier approach the ratio desired.
16. The method of obtaining a linear amplification characteristic from an amplifier employing an electron emission tube having a non-linear amplification characteristic which includes obtaining and rectifying energy which is a function of the input energy, obtaining and rectifying energy which is a function of the output energy, differentially combining the rectified energies to obtain a normal resultant when the amplification ratio is that desired, and utilizing changes from the normal resultant to vary the grid bias of a tube to make the amplification ratio of the amplifier approach that desired.
17. The method of controlling the ratio of amplification of an amplifier employing an electron emission tube which includes continuously comparing the input and output energies to ascertain the relation between their ratio and the desired ratio, and continuously utilizing departures of their ratio from the desired ratio to vary a tube characteristic to lessen the departure of the actual ratio from the desired amplification ratio.
18. An electron emission tube amplifier stage reproducing in its output circuit a substantially exact amplified copy of input energy comprising a source of input energy, an input circuit, an output circuit, an electron emission tube subjected to grid rectification thereby having a characteristic other than that desired, and means for applying to the input circuit of the tube energy derived from the input and output circuits of the tube which combines with and so alters the effective wave form of the tube input energy that the output energy is related to the original input energy in accordance with the desired characteristic, reproducing the input energy in substantially exact amplified form.
19. An electron emission tube stage of desired characteristic comprising a source of input energy, an input circuit, an output circuit, an electron emission tube having a characteristic other than that desired, means for differentially combining portions of the input and output energies, and means for combining the differential energy with the input energy to obtain an altered effective input on the tube grid resulting in output energy which is related to the original input energy in accordance with the desired characteristic.
20. An electron emission tube stage of desired characteristic comprising a source of input energy, an input circuit, an output circuit, an electron emission tube having a characteristic other

- than that desired, auxiliary circuits including rectifying means so coupled to the input and output circuits that the rectified currents are equal when the characteristic is that desired, means for differentially combining the rectified currents, and means responsive to the resultant rectified current for altering the tube characteristic to lessen the resultant current.
21. In combination, an electron emission tube amplifier stage reproducing in its output circuit a substantially faithful amplified copy of the input energy including a tube having a control electrode, an input circuit for feeding energy to the electron emission tube stage, an output circuit for delivering energy from the electron emission tube stage for utilization, and means for automatically adjusting the value of the bias on the aforesaid control electrode comprising an auxiliary detector, means coupling the auxiliary detector to the output circuit of the electron emission tube stage, an impedance arranged to be fed by the output of the auxiliary detector, and means coupling said impedance to the aforesaid control electrode to impress a potential thereupon dependent upon the magnitude of the flow of rectified current through said impedance.
22. An electron emission tube arrangement for preventing distortion due to grid rectification comprising several electron emission tube stages, grid biasing means therefor, input and output circuits for said stages, circuits, coupled with said input and output circuits, including rectifying and impedance elements, and means for automatically varying the biasing means according to the rectified current flow through said rectifying and impedance elements in order to control in desired fashion the characteristic of the arrangement such that despite grid rectification the ratio of output to input is substantially a straight line.
23. In electrical apparatus of the character described, a pair of electron discharge devices each having an anode, a cathode and a control electrode, said devices being connected in push-pull fashion, an input circuit for said devices, an output circuit for said pushpull connected devices, said devices being subject to grid rectification whereby its characteristic curve is given a form producing distortion in the energy appearing in the output circuit of said pushpull connected electron discharge devices, and means, connected with electrodes of said devices for subjecting automatically and purely electrically said electrodes to more positive potentials when said devices tend to introduce distortion such that the effects of grid rectification are substantially compensated and thereby eliminating substantially the distortion produced by the grid rectification.
24. In electrical apparatus of the character described, an amplifier producing distortion in energy of amplitude beyond a certain value applied to its input circuit, an amplifier preceding said distortion producing amplifier and feeding energy to be amplified to said distortion producing amplifier, and means associated with said amplifiers for increasing the amount of energy fed to the input circuit of said distortion producing amplifier when distortion begins to occur therein, whereby the output of said distortion producing amplifier is substantially an exact reproduction of energy fed to its input circuit despite the inherent distortion characteristic of said amplifier.
25. In electrical apparatus for producing exact but amplified replicas of desired electrical waves, an electron discharge device amplifier element subjected to grid rectification thereby producing,
- normally, distortion in the shape of the wave traversing said apparatus, an amplifying electron discharge device preceding said element and feeding waves thereinto, and a circuit, coupled to said preceding electron discharge device and said amplifier element responsive to the distorting conditions in said element, subjecting said preceding amplifying electron discharge device to potentials such that said preceding device introduces in said amplifying element correcting potentials compensating and substantially eradicating the distortion normally introduced by said amplifying element.
26. In electrical apparatus, an amplifier having an adjustable ratio of amplification, input and output circuits coupled to said amplifier, a circuit coupled to said input and output circuits automatically controlling and maintaining constant the ratio of output to input energy of said amplifier over a wide range including points where normally grid rectification in said amplifier would occur, and, means for varying the ratio of output to input energy of said amplifier maintained by said automatic ratio controlling circuit.
27. In electrical apparatus, an amplifier having an input circuit and an output circuit, unidirectional electric current devices coupled to said input and output circuits, means coupling the outputs of said unidirectional devices to said amplifier to maintain constant the ratio of output to input energy, and additional means for varying said ratio.
28. An amplifier system for producing amplified exact replicas of waves comprising a pair of cascaded electron discharge devices each having an input circuit and an output circuit and an anode, a cathode and a grid, the output circuit of the first of said devices being coupled to the input circuit of the second device, a source of potential and a resistor serially connected between the grid and cathode of the first device, a connection including a source of potential from the grid of the second device to the end of said resistor connected to the cathode of the first device, and a connection from the cathode of the second device to the end of said resistor to which the grid of the first mentioned device is connected whereby grid current flow of the second device varies the potential on the grid of said first device in such a way as to introduce into said second device potentials to compensate for the distortion caused by the grid current flow in said second device.
29. An amplifying system comprising a first pair of electron discharge devices each having an anode, a cathode and a grid, a second pair of electron discharge devices each having an anode, a cathode and a grid, input and output circuits connected to the input and output electrodes of said pairs of devices, the output circuit of said first pair of devices feeding the input circuit of said second pair of devices, a resistor connected between the cathodes and grids of said second pair of devices, and a connection from the end of said resistor to which the cathodes of said second pair of devices are connected and the grids of said first mentioned pair of devices whereby grid current flow in said second pair of devices causes a variation in potential across said resistor which variation in potential alters the grid bias on said first mentioned pair of devices in such a way as to introduce compensating potentials into said second pair of devices as to reduce distortion caused by the grid current flow in said second pair of devices.
